UNITED STATES PATENT OFFICE.

JOHN M. HOPWOOD, OF DORMONT, PENNSYLVANIA.

METHOD OF AND MEANS FOR FORMING BAFFLES IN BOILERS.

Application filed April 28, 1922. Serial No. 557,192.

To all whom it may concern:

Be it known that I, JOHN M. Hopwood, residing at Dormont, in the county of Allegheny and State of Pennsylvania, a citizen of the United States, have invented or discovered certain new and useful Improvements in Methods of and Means for Forming Baffles in Boilers, of which improvements the following is a specification.

- 10 By reason of the arrangement of the tubes in horizontal water tube boilers, as for example, of the Babcock & Wilcox type, so that the tubes of one row will alternate horizontally with the tubes of adherent rows, 15 great difficulty is experienced in forming baffles. It is the practice in forming baffles at right angles to the tubes to employ blocks of appropriate shape but having circular notches at the juncture of the sides so that 20 the block will not only fill the space between four tubes (two in one horizontal row, two in a vertical row) but will also partially enclose the tubes of a nest and project such a distance between adjacent tubes as to contact with the edges of blocks in adjacent 25 spaces. Because of the necessary dimensions of these blocks and the distances between adjacent tubes, it is necessary to force the tubes apart in order to place the blocks in position. 30 and when released, the tubes will spring back to lightly grip the blocks.

By reason of such construction of baffle, a tube cannot be replaced without destroying the blocks or some of the blocks bearing on 35 the old tube and inserting new blocks after the new tube has been secured in position. And further, it is difficult to ensure tight joints between edges of adjacent blocks and as in this construction of baffle, there will be 40 four joints between blocks around each tube, a small leakage at each joint will be detrimental to the operation of the boiler.

The object of the invention is to provide for the formation of a baffle between the 45 tubes of a boiler in sections, each section being molded in situ. It is a further object of the invention to provide a mold or shell for the shaping of the sections, said mold being capable of being collapsible or distorted to facilitate its being placed in position between rows of tubes in a boiler. The 50 invention is hereinafter more fully described and claimed.

In the accompanying drawings forming a part of this specification, Fig. 1 is a transverse section of the tubes of a horizontal water tube boiler illustrating the manner of inserting the molds between the tubes; Fig. 2 is a sectional plan on an enlarged scale showing a portion of a completed baffle and 60 also the manner of introducing the molds; Fig. 3 is a side elevation on an enlarged scale of a portion of a mold; Fig. 4 is an edge view of a collapsed mold; Fig. 5 is an edge view of the mold expanded; Fig. 6 is a 65 view similar to Fig. 1 illustrating the method of forming a horizontal baffle; Fig. 7 is a sectional plan view on a plane indicated by the line VII—VII, Fig. 6; Figs. 8 and 9 are end and side elevations of the 70 mold employed in forming the horizontal baffles.

In the practice of the invention a mold capable of being so collapsed or reduced in transverse dimensions that it may be inserted between adjacent diagonal rows of tubes, as shown in Fig. 1 is slid diagonally to its position longitudinally and then if necessary to attain its proper transverse position, the mold is turned axially until its sides are at 80 right angles to or approximately so to the tubes, as shown to the right in Fig. 2. In the construction shown in Figs. 1 to 6, the edges of the mold are formed with circular notches formed on arcs or circles having 85 radii equal to those of the tubes, for the reception of the tubes when the mold is in position. After the mold has been adjusted to position it is expanded forcing the side walls apart and the mold filled with suitable 90 plastic refractory material. After a section of the baffle has been formed, other sections are formed in a similar manner. While each mold section may be charged with the refractory material before another is placed 95 in position, it is preferred that all the molds should be placed in position, and that the refractory material be charged into alternate molds. When the material is forced into a mold, it will cause a bulging of the edge 100 walls as at *a* and when the succeeding mold is charged its edge wall will be caused to conform with the convex surfaces of the previously charged mold as shown in Fig. 2.

While the invention is not limited as 105 regards its broad features, the use of any

specific construction of mold whereby it may be collapsed or otherwise distorted for insertion between the tubes, the construction shown has been found to be well adapted 5 for building up of baffles as described. The mold or shell has its side walls 1 comparatively stiff, but not necessarily rigid, while the opposite walls 2 are flexible to permit of the side walls being moved inward 10 towards each other. In practice, the walls 1 are preferably made of heavy and comparatively stiff paper or other suitable material. Circular notches 3 are formed in the edges of the sides 1 for the reception of 15 the tubes of the boiler and the sides are made of such widths that the portions 4 intermediate the notches will project suitable distances between adjacent tubes preferably distances equal to one-half the diameter of 20 the tubes.

The lower end of the mold or shell is closed with flexible material corresponding in character to that forming the edge walls 2. The upper end 5 of the shell is made 25 of any suitable shape to facilitate the attachment of a nozzle for forcing in air for expanding the shell and for charging the latter with the refractory material.

When building a baffle, the mold or shell 30 is collapsed, the side walls 1 being pressed together and the flexible edge walls folding in, as shown in Figs. 1, 2 and 5. The collapsed mold is then pushed in between adjacent diagonal rows of tubes, its sides 1 being 35 parallel with the tubes, or sufficiently so to permit of the easy insertion of the shell. After the mold or shell has reached the desired longitudinal position, it is rotated axially through an arc of ninety degrees in 40 which movement the portions intermediate the notches will pass between adjacent tubes and the latter be partially enclosed. In its collapsed or folded shape, the side walls 1 will be nearly in contact so that there will 45 be little difficulty in thus turning the shell, but all difficulty will be avoided by making the walls resilient and capable of being flexed transversely. After being turned to a position at right angles to the tubes, the shell or mold is subjected to internal pressure to force the side walls apart, such expansion being effected by air pressure before the refractory material is charged into the mold, or by forcing the refractory material 50 into the molds.

If desired, reinforcing rods 6 may be incorporated in the sections said rods being placed in position either before or after the molds or shells are charged with the plastic 60 material. These rods in addition to strengthening the sections may by extending their ends beyond the baffle sections, serve to support deflecting walls above or below the tubes.

65 While it is preferred to make the side

walls of the mold or shell, when forming vertical baffles, comparatively stiff but capable of some degree of flexure, as such stiff portions facilitate the placing of the molds when forming vertical baffles or baffles at 70 right angles to the tubes, the entire walls may be made flexible. Such construction, i. e., all parts of the mold flexible, is especially desirable in forming horizontal baffles or baffles parallel with the tubes as shown in 75 Figs. 6 and 7. In forming the horizontal baffle it is preferred that the mold or shell 7 should be of a comparatively heavy fabric, such as canvas, and of a length equal to the desired length of baffle, or a fraction of such 80 length. In order to facilitate the placing of the mold or shell in position, it may be partially inflated and hence if formed of porous material, a thin coat of paint may be applied to the surface of the material or 85 it may be rendered impervious under light pressures in any other suitable manner. When thus inflated, the mold is passed laterally to the space between the nest of tubes 90 b, which it is designed to occupy, and allowed to rest on the lower tube. Refractory material in a semi-fluid or plastic condition is then forced into the mold or shell causing it to expand and take a comparatively broad bearing on the tubes.

95 It will be understood that the exposed portions of the mold or shell will be burned away but the portions between the tubes and refractory material and the portions between contiguous parts of the refractory material will be charred and remain positive as a seal for the joints, until a tube is removed. It will be readily understood that in removing a tube the charred material will 100 be scraped away and the opening through the baffle will be slightly larger than the tube so that a new tube can be easily inserted. Hence it is preferred to make the edge walls 3 of the form of mold shown in Figs. 1 to 6 of comparatively thick but flexible 105 material.

I claim herein as my invention:

1. The method herein described of forming baffles in boilers, which consists in forming the baffle in sections, each section being 115 shaped in position in the boiler.

2. The method herein described of forming baffles in boilers, which consists in placing a series of molds or shells, each having the shape and dimensions of a portion of the baffle, in position between the tubes of the boiler, and then filling such mold or shell with a suitable material.

3. A shell or mold having normally the shape and dimensions of a section of a baffle 125 and adapted to be collapsed or distorted to permit of its being inserted between the tubes of a boiler.

4. A shell or mold consisting of side and edge walls, two of said walls being compar- 130

atively stiff and the other walls flexible, having their edges notched, and having the side walls having a width substantially equal to the distance between centers of tubes in adjacent rows, and notched to fit towards and from each other.

5 around the tubes of adjacent rows. In testimony whereof, I have hereunto set

5. A shell or mold having side walls formed of flexible material and my hand.

JOHN M. HOPWOOD.
